UNITED STATES PATENT OFFICE.

JAMES P. CLIFTON, OF BUFFALO, NEW YORK, ASSIGNOR, BY DIRECT AND MESNE ASSIGNMENTS, TO WATER POWER VACUUM CLEANER CO., OF BUFFALO, NEW YORK, A CORPORATION OF NEW YORK.

VACUUM CLEANING APPARATUS.

1,080,420.

Specification of Letters Patent.

Patented Dec. 2, 1913.

Application filed January 17, 1911. Serial No. 603,060.

To all whom it may concern:

Be it known that I, JAMES P. CLIFTON, a citizen of the United States, residing at Buffalo, in the county of Erie and State of New York, have invented new and useful Improvements in Vacuum Cleaning Apparatus, of which the following is a specification.

This invention relates to improvements in suction cleaning apparatus, and primarily to that class of apparatus in which an air suction is produced by the aid of a fluid jet or stream.

The principal object of the invention is to secure a continuous air suction of sufficient strength by injecting a stream or jet of fluid under fairly high pressure into the dust-laden air conveying element or pipe extending from the cleaning tool.

20 The invention also relates to certain details of construction which will be herein-after described and perhaps claimed, reference being had to the accompanying drawings in which a preferred adaptation of the apparatus is illustrated.

Figure 1 is a central longitudinal section through the improved suction cleaning apparatus. Fig. 2 is a detached view of the top cap and nozzle. Fig. 3 is a horizontal section on line *a a*, Fig. 1. Fig. 4 is a detached view of the valve nozzle.

In referring to the drawings in detail, like numerals designate like parts.

The apparatus consists of a suction producing element having a hollow body, and a removable cap for said body carrying a fluid injecting nozzle provided with a needle valve, said nozzle being connected to a source of fluid under pressure, a discharge pipe leading from the suction element, a flexible tube connected at one end to a cleaning tool and at its opposite end to a tubular coupling projecting from the hollow body of the suction apparatus element.

45 The hollow body 1 of the suction apparatus element in the preferred adaptation shown in the accompanying drawings, is of a cylindrical form. An interiorly screw-threaded portion 2 of smaller diameter depends from the cylindrical body 1, being connected thereto by means of a contracted intermediate portion 3. The top mouth of the hollow body is closed by a removable cap 4 which has an interiorly screw-threaded

depending flange 5 which screws upon the 55 screw-threaded top margin of the hollow body. A packing 6 is interposed between the cap and hollow body to secure a tight non-leaking joint.

A tubular coupling 7 extends from the 60 side of the tubular body 1, to which a flexible tube 8 is connected by an exterior tubular connection 9, said connection being fitted snugly around the adjacent ends of the tubular coupling 7 and the flexible tube 8. The 65 lower portion of the body 1 has tapered walls, 10, and the coupling 7 is extended so as to project in longitudinal alinement with said tapered walls. By this means the air enters the tubular body directly in a straight 70 line, and is not deflected until it gets to slightly above the contracted portion 3.

A cleaning tool of any well-known form is suitably attached to the outer end of the flexible tube 8.

75 A tubular nozzle is preferably formed separate from the cap 4, being screwed into a central vertical screw-threaded portion 11 depending from the cap. The advantage of this construction is that the nozzle may be 80 adjusted vertically toward or from the contracted lower end of the portion 11. The nozzle consists of an upper tubular portion 12 and a reduced tubular portion 13, which in part is exteriorly screw-threaded to screw 85 within the portion 11. The lower end 14 of the lower tubular portion 13 is made solid and is tapered, reducing in size in a downward direction. The nozzle is vertically adjustable in the portion 11 to vary the size 90 of the annular outlet opening 15 between the circular inner surface of the lower end of the portion 11 and the exterior surface of the lower end 14 of the nozzle. This provides a means for varying the rapidity of 95 flow of fluid through the portion 11 and also for varying the volume of the flow. The lower end of the tubular portion 13 is provided with side openings 16 which form outlets, as shown by arrows in Fig. 1.

100 An enlarged socket 17 is formed at the upper extremity of the tubular nozzle, and is provided with a knurled flange constituting a convenient turning means for said nozzle. The socket 17 is interiorly screw-threaded for attachment to a pipe 18 extending from a source of fluid under pressure.

2
A stuffing box 19 is arranged in the upper extremity of the tubular member 11 to prevent leakage of fluid around the nozzle where it passes through the upper end of the tubular member. A discharge pipe 20, which extends to any convenient source of discharge, such, for instance, as a sewer, has its upper end screwed into the lower tubular portion 2 of the suction producing element.

10 The operation of this improved apparatus is as follows: The water or other fluid under pressure being turned on, a continuous jet or stream is projected vertically downward through the lower portion of the tubular body into the discharge pipe, and creates a partial vacuum in the said tubular body, reducing the suction in the flexible tube sufficient to draw the dirt, dust or other impurities from the articles to be cleaned, through the openings in the cleaning tool. The air containing the impurities passes from the flexible tube through the suction producing element downward, out through the discharge pipe to any convenient source of discharge. The volume of the jet or stream may be regulated to correspond with the strength of the pressure of the fluid or other liquid by adjusting the valve needle 30 in the proper direction.

One of the greatest difficulties with vacuum apparatus used for cleaning carpets and other fabrics has been to regulate the strength of the vacuum to the area of the suction opening in the tool, and thus provide on one hand sufficient suction to properly clean the carpet or other fabric and avoid on the other hand the creation of a sufficiently strong suction to pull out the nap or a portion of the material and thereby injure or destroy the carpet or other fabric. One of the great advantages of applicant's invention is that this serious difficulty is entirely overcome by his improved structure. 45 This is accomplished by aid of the adjustable nozzle which regulates the volume of water flow to correspond to the rapidity of pressure of the same and through it regulates the amount of strength of the air 50 suction.

The main advantages of this improved apparatus are that it is absolutely non-clogging, that it is extremely simple, cheap and durable in construction and certain and sure 55 in operation, and that it dispenses with, and entirely eliminates the use of any dust collecting element or suction pump.

I claim:

1. In an apparatus of the class described, 60 a suction producing element having a hollow one-piece body provided at one end with a removable cap and at the other end with a discharge opening, said hollow body being also provided with a tubular side inlet adjacent the discharge opening and directed

toward the latter, the cap being provided with an axially extended tubular member terminating within the hollow body adjacent the discharge end in a contracted portion having a central opening, and a hollow fluid injecting nozzle carried by the tubular extension of the cap, said nozzle having means exterior to the hollow body for attachment to a source of fluid under pressure and within the tubular extension of the cap being provided with means for controlling the flow of liquid through the open terminal portion of the said hollow extension within the body.

2. In an apparatus of the class described, 80 a suction producing element provided with a hollow body having a removable cap at one end and provided at the other end with a contracted discharge opening, said hollow body having a side neck opening thereinto between the cap and the contracted discharge opening and directed toward the latter, said neck being shaped to receive a flexible tube, means at the discharge end of the hollow body for connecting a discharge pipe thereto, a fluid injecting nozzle carried by and extending adjustably through the cap in line with the discharge opening, and means on the nozzle exterior to the cap for coupling the nozzle to a source of fluid under pressure.

3. In an apparatus of the class described, 95 a suction producing element having a hollow body and a removable cap and provided with a contracted discharge opening at the end remote from the cap, said body having a 100 tubular neck extending from one side thereof and opening into the body between the cap and contracted discharge end and directed toward the discharge end at an angle to the longitudinal center line of the hollow body, a fluid injecting nozzle carried by the cap and adjustable therethrough, said nozzle being provided with a needle valve at one end and at the other end exterior to the cap with means for connecting the nozzle to a 105 source of fluid under pressure, a discharge pipe connected to the discharge end of the hollow body, and a flexible tube connected to the side neck.

4. In an apparatus of the class described, 115 a suction producing element having a hollow body provided with an outlet at one end and at the side provided with a tubular coupling or neck, a removable cap for the end of the body remote from the discharge end, said 120 cap having a depending axially extended and internally screw-threaded portion terminating adjacent the discharge end of the body and there provided with an axial opening formed with a valve seat, a hollow fluid 125 injecting nozzle having screw threads adapted to the internally threaded part of the depending portion of the cap and terminating at one end in a tapered valve adapted to the valve seat and also provided with side out- 130

lets adjacent the valve, the nozzle being provided at the end remote from the valve with means for connection to a source of fluid under pressure, and a flexible tube connected to the tubular coupling or neck at the side of the body.

5. In a device of the class described, a suction producing element having a hollow body with a contracted intermediate portion and a cylindrical lower portion depending from the contracted intermediate portion and also provided with a side inlet adjacent to and above the contracted intermediate portion, a removable top cap fitted on the hollow body and having a tubular depending interiorly screw threaded portion terminating adjacent to and above the contracted portion of the hollow body and there provided with an axial opening, and a tubular nozzle in part exteriorly screw threaded and fitted within the tubular depending portion, said tubular nozzle having side outlets.

6. In a device of the class described, a suction producing element having a hollow body with a contracted intermediate portion and a cylindrical lower portion depending from the contracted intermediate portion and also provided with a side inlet adjacent to and above the contracted intermediate portion, a removable top cap fitted on the hollow body and having a tubular depending interiorly screw-threaded portion terminating adjacent to and above the contracted portion of the hollow body and there provided with an axial opening, and a tubular nozzle in part exteriorly screw-threaded and fitted within the tubular depending portion, said tubular nozzle having side outlets, and a solid lower end adapted to the open end of

the depending tubular portion of the removable cap. 40

7. In an apparatus of the class described, a suction producing element having a hollow body and a cap therefor provided with an extended support, and a longitudinally adjustable fluid injecting nozzle carried by the support and connected to a source of fluid under pressure, said nozzle terminating in a valve needle within the support, the needle at the end of the nozzle and the support 50 being constructed to coact to control the flow of fluid through the nozzle, and a discharge pipe leading from the suction producing element.

8. A device of the class described consisting of a hollow body having a contracted intermediate portion and a cylindrical lower portion depending therefrom, a top cap on the hollow body having a tubular depending interiorly screw-threaded portion terminating adjacent the contracted portion of the hollow body in line therewith and provided with an axial passage therethrough, and a tubular nozzle in part exteriorly screw threaded and fitted within the tubular depending portion, said tubular nozzle having side outlets and a solid lower end within the tubular depending portion and exterior to the hollow body being provided with means for connection to a source of fluid under 70 pressure and with means whereby it may be turned about its longitudinal axis for longitudinal adjustment. 60 65
